DAVID W. TAYLOR, OF WASHINGTON, DISTRICT OF COLUMBIA

TUNNEL BOAT

Application filed April 11, 1930. Serial No. 443,399.

In the screw propulsion of vessels, the water in the propeller race behind the screw has a sternward and a rotary motion. For most vessels the propeller race is clear of the hull. Any structure built to regain energy that is usually carried off in the race must be fitted within the race. There are, however, some vessels which give an opportunity to utilize the momentum of the race by structures around it. This is notably the case in tunnel boats.

In my application, Serial No. 364,494, filed May 20, 1929, I have utilized the diverging rear end of the tunnel of a tunnel boat, on the diverging sides of which I develop a forwardly propelling force component, by first stopping the rotation of the race in a non-diverging portion thereof, and there developing this component by special means in the diverging portion of the tunnel after the race leaves the means for stopping the rotation.

My present invention is to develop this forwardly propelling pressure or component from the race on the diverging surfaces or walls of the rear end of the tunnel by means wholly within the divergent portion of the rear end of the tunnel and that simultaneously stops rotation of the race and develops the forwardly propelling pressure therefrom.

For this purpose I preferably use fins or ribs fitted on the diverging surfaces of the rear ends of the tunnels aft of the propeller, which stop the rotation of the race in the immediate vicinity of the diverging surface of the tunnel. These fins or ribs change the rotary direction of movement of the water of the race and direct it aft to raise the pressure on the diverging walls of the race and thereby obtain a useful forwardly propelling action on the diverging sides.

Referring to the drawings, in which like parts are similarly designated:

Figure 1 is a vertical section on line 1—1 of Fig. 3 of a tunnel showing my invention;

Fig. 2 is a horizontal section on line 2—2 of Fig. 1;

Fig. 3 is an end elevation;

Fig. 4 is an end elevation of a rear-end of a tunnel having elliptical section and diverging walls;

Fig. 5 is a horizontal section of a tunnel formed by a depression in the side of a vessel and open at the side of the tunnel.

Fig. 6 is an elevation thereof;

Fig. 7 is a section on line 7—7 of Fig. 5;

Figs. 8, 9 and 10 show sections of different forms of fins or ribs.

Referring to Figures 1—3, the stern overhang of the hull is indicated at 11 and it carries the tunnel 12 substantially rectangular in cross-section, open at its front end and has preferably a circular portion 13 in which the propeller 14 rotates.

The propeller is driven by a shaft 15.

The tunnel is closed on all four sides, has side walls 16 diverging at the rear end. Only the side walls diverge to reduce the draft of the boat. These side walls 16 are provided with projecting fins, ribs or plates 17, preferably but not necessarily projecting beyond the circular path of tips of the propeller blades.

The race leaving the propeller 14 has a rotary movement and encounters the fins 17 on the diverging walls of the rear end of the tunnel that stop rotation of the race or that portion of it in the region of the fins which direct the water aft along the diverging walls of the tunnel on which the pressure develops. The pressure by reason of acting on the walls which are inclined to the direction in which the pressure is developed exerts a forwardly driving component useful in assisting the propulsion of the vessel.

The fins, ribs or plate may have various shapes in cross section as shown at 17, 18, 19 in Figs. 8, 9 and 10 respectively and are generally of the shape of the angles fastened to inner, diverging walls of the tunnel and may vary in width especially in tunnels substantially rectangular in cross section. In Fig. 2 these fins 17 increase in width toward their aft ends.

In Fig. 4 I have also shown a tunnel closed on all sides but substantially elliptical in cross section in its diverging portion 16 having fins 17 directed radially.

In Figs. 5, 6, 7, I have shown a tunnel formed by a depression 20 in the side of a vessel and radial ribs in the diverging por-

tion 21 just aft of the propeller. This tunnel is open at the side towards the water.

In any case whether the tunnel aft of the propeller is rectangular in cross-section, circular, elliptical, entirely closed on its sides or open at one side, the fins are to be applied to the diverging walls of the rear end of the tunnel aft of the propeller.

In general wherever the propeller race follows a hull surface which is at such angle to the axis of the race, as it leaves the propeller that an increase of pressure would result in an increase of forward thrust upon the hull, the installation of fins will produce an increase of pressure upon the hull, the installation of fins to produce an increase of pressure upon the hull surface by checking the rotation in the race will be advantageous.

This local increase of pressure will also cause the race to hug the surface better and it is this indirect action of the fins which is particularly helpful in diverging tunnels because by reason of it the water more nearly maintains the pressure velocity relations of a perfect fluid, and the checking of the sternward velocity as the tunnel expands results in the production of a useful forward thrust. Longitudinally the fins may be of uniform width or not. Fins in a circular diverging tunnel have little to gain by varying width, Fig. 2, but those on the sides of a tunnel of approximately rectangular section may be widened toward their after ends with advantage.

35 I claim—

1. In a tunnel boat, the combination with a tunnel diverging at its rear end, and a propeller in the tunnel; of means in said diverging end to simultaneously check race rotation and produce a forwardly propelling component on the diverging walls of said rear end aft of the propellers.

2. In a tunnel boat, the combination with a tunnel diverging at its rear end and a propeller in the tunnel; of means projecting from the diverging walls of said tunnel to check race rotation and simultaneously produce a forwardly propelling force on the diverging walls of said rear end aft of the propeller.

3. In a tunnel boat, the combination with a tunnel and a propeller therein, said tunnel diverging from the propeller position to its rear end; of fins projecting from the diverging walls of said race.

4. In a tunnel boat, the combination with a tunnel and a propeller therein, said tunnel diverging from the propeller position to its rear end; of fins projecting from the diverging walls of said race, increasing in width from the propeller position to the rear end of the tunnel.

5. In a tunnel boat having a tunnel substantially rectangular in cross section and closed on its four sides, a propeller in the

tunnel, said tunnel having its two sides diverging; of fins on the diverging sides extending from the propeller position aft that increase in width.

In testimony that I claim the foregoing as my invention, I have signed my name.

DAVID W. TAYLOR.
